CARBON-FREE OPERATION OF INTERNAL-COMBUSTION ENGINES

Elmer Ryder, Aurora, Ill.

Application December 20, 1948, Serial No. 66,328

6 Claims. (Cl. 123—191)

1

The present invention relates to improvements in internal combustion engines, and more particularly concerns a solution of the problem of overcoming the detrimental effects of the carbon resulting from the combustion of fuel in the operation of such engines.

Carbon particles formed in the combustion of the motivating fuel in the operation of internal combustion engines, of both the ignition type and diesel type, have a highly abrasive character. In the conventional internal combustion engine these carbon particles work back from the combustion chamber in the cylinder head past the pistons and into the crank case oil.

Possibly the principal cause of cylinder scoring and wear is attributable to the carbon as it finds its way past the pistons. In the crank case oil the carbon is distributed to all of the bearing parts which are lubricated by the oil. Consequently engine wear and deterioration are grossly excessive in spite of vastly improved mechanisms, metallurgical practices and machining methods.

Elaborate precautions are generally exercised to minimize deterioration caused by carbon. Thus, extremely close fitting piston rings with scavenger devices, carbon controlling expedients, and the like are utilized on the pistons, with the result that the cylinder wall which is the very bearing surface that should be most efficiently lubricated and which is closest to the carbon source and most prone to the detrimental abrasive effects of the carbon is virtually lubrication starved. Furthermore, oil filters are utilized for the crank case oil with the prime objective of removing carbon from the oil. Nevertheless the crank case oil must be completely flushed out and replaced by a fresh oil supply periodically because of the load of carbon with which it soon becomes polluted. When the crank case is drained, a heavy carbon sludge is usually found and the oil has the characteristic black color due to the carbon particles suspended therein. If it were not for the carbon pollution a good grade of motor oil would last indefinitely and would require replacement merely by way of addition for oil lost by leakage or volatilization.

An important object of the present invention is to improve the operation of internal combustion engines by substantially preventing escape of carbon from the combustion chamber into the cylinders and the crank case.

Another object of the invention is to remove directly from the combustion chamber of an internal combustion engine carbon produced in

2

operation, and in such a manner that escape of carbon past the pistons is practically eliminated.

A further object of the invention is to provide improved means for scavenging carbon from internal combustion engines.

Still another object of the invention is to provide an improved method of scavenging carbon from the combustion chamber of an internal combustion engine.

10 Other objects, features and advantages of the present invention will be readily apparent from the following detailed description of one embodiment thereof, taken in conjunction with the accompanying drawings, in which:

15 Figure 1 is a fragmentary longitudinal sectional view through the cylinder of an internal combustion engine;

20 Figure 2 is a fragmentary sectional view taken substantially on the line II—II of Fig. 1;

25 Figure 3 is a schematic view of an internal combustion engine embodying the features of the invention; and

30 Figure 4 is a schematic view showing a modified construction.

25 According to the present invention, carbon is removed directly from the combustion chamber of an internal combustion engine by way of a sump draining from the lowest point in the combustion chamber, while fuel intake and gas exhaust are accomplished in a high part of the combustion chamber.

35 In the very early history of internal combustion engines it was thought advisable to have the exhaust port and valve at the lowest point in the combustion chamber. This was soon found to be quite impractical, however, because the carbon passing through the exhaust port quickly cut the valve and its seat as well as the valve stem into such a state of deterioration that the 40 engine would lose power to a quite undesirable degree. In the long interval since then it has always been found desirable to have the intake and exhaust ports in a high portion of the combustion chamber so that the natural gravitational 45 tendency of the carbon would be away from these ports. Consequently the carbon has either deposited on the walls of the combustion chamber and on the piston head or has escaped past the piston into the crank case, with all of the 50 deterioration factors thus created.

By the present invention all of the desirable features of having the intake and exhaust ports at a high point of the combustion chamber or retained, but the deterioration factors attendant upon carbon escape into the crank case are

eliminated by removing the carbon from the lowest point in the combustion chamber in the operation of the engine.

Carbon removal is enhanced by encouraging gradual, incremental displacement of crank case oil past the head of the piston into the combustion chamber to act as a carbon flushing agent in which the carbon becomes entrained in heavy concentration to form a sludge which gravitates into the carbon sump and is drained from the sump. Thus, instead of requiring a periodic change of oil, an engine utilizing the present invention will require merely a gradual addition of oil to the crank case. The oil in the crank case remains substantially clean at all times to perform its lubricating function to best advantage. The loss of oil from the crank case due to the permitted or even encouraged carbon flushing seepage into the combustion chamber will at least not put the engine user to any disadvantage from the oil consumption standpoint as compared with prior practice since over a period of time no more oil need be consumed by the engine due to the carbon flushing seepage than would be consumed by the periodic oil change heretofore required. The probabilities are, however, that there will be an actual saving in oil consumption in addition to the tremendous saving effected in the engine due to the saving in wear on the cylinder walls and the various bearings lubricated by the crank case oil by reason of the elimination of the abrasive deteriorating effects of carbon particles.

By way of example the invention has been shown in Figures 1 and 2 as applied to a well known type of internal combustion engine including a horizontal cylinder 10 within which a piston 11 operates reciprocably to drive a piston rod 12 which is connected internally thereto through the medium of the usual wrist pin 13. The cylinder has thereabout the usual water jacket 14. Removably secured to the end of the cylinder structure is a cylinder head 15, the usual attaching bolts 17 being provided for securing it in place.

Within the inner face of the cylinder head 15 is formed a combustion chamber cavity 18. This cavity cooperates with the outer end of the cylinder bore to provide a combustion chamber, and extends laterally of the cylinder bore to communicate with fuel intake and exhaust passages, one of which identified at 19 is shown in Fig. 1, and which passages are controlled by the usual respective poppet valves, identified at 20. Fuel ignition is provided for by a spark plug 21 carried by the cylinder head 15. As will be observed, the fuel intake and exhaust passages are located in the highest portion of the combustion chamber. Consequently, in the operation of the engine carbon created as a result of combustion of fuel in the combustion chamber being relatively heavy tends to gravitate toward the lowest portion of the combustion chamber.

For receiving the carbon, a sump recess 22 is provided at the lowermost end of the combustion chamber cavity 18 in the cylinder head 15. By preference this sump recess is of only small dimension so as not to interfere with the compression characteristics of the combustion chamber cavity 18, and all surfaces leading to the sump recess or depression are smoothly curved to avoid any ledges on which carbon might tend to accumulate. As seen in Figs. 1 and 2, all adjacent surfaces taper into the sump recess 22, there being a ramp surface 23 which tapers from

the edge of the cylinder bore. Thus, in the operation of the engine, carbon formed by the explosive combustion of fuel works down the walls defining the combustion chamber cavity 18 into

5 the sump 22, and since the piston 11 moves on compression stroke to the end edge of the cylinder bore any carbon that may tend to deposit in the cylinder bore on the power stroke of the piston is scavenged therefrom by the piston and drops down into the carbon scavenging sump 22.

10 In order to enhance the carbon scavenging action, piston rings 24 on the piston 11 are preferably of a character to permit a slight seepage of crank case oil outwardly thereby and such 15 oil will serve to flush the carbon as a sludge downwardly into the scavenging sump 22.

15 In order to remove the carbon sludge from the sump 22 while the engine is in operation and without disturbing the compression within 20 the combustion chamber means are provided for draining the sump 22 without opening the combustion or compression chamber to loss of compression. Herein such means comprises a tapered rotary pocket valve 25 rotatably closely 25 bearinged in a complementary tapered bearing bushing 27 which is press fitted within a complementary tapered bore 28 provided in a transverse boss 29 integral with the lower end of the cylinder head 15 and into which the sump 30 22 drains.

25 The bushing 27 has an opening 30 in the side thereof which is complementary in size to and in registration with the sump 22 and forms a part of the sump cavity. In the periphery of 35 the valve plug 25 is provided a uniform series of drainage pits or pockets 31 which are of a length and width and are so disposed that they are adapted to register substantially with the sump opening 30 in the bushing. Thereby carbon sludge will drop from the sump into which ever one of the pits 31 is in registration with the sump.

40 Since the capacity of each of the drainage pits or pockets 31 is necessarily limited, means are provided for turning the drainage valve 25 so as to bring the drainage pits 31 successively into registration with the sump 22 while at the same time moving the loaded drainage pit away from the sump and into registration with a downwardly directed cleanout opening 32 in the bushing 27 registering with a cleanout opening 33 in the lower side of the valve boss 29. The means for turning the valve plug 25 herein comprises a worm gear 34 secured to the outer end of the plug in a suitable fashion and meshing with a worm 35 carried by a shaft 37 journaled in a shaft bracket 38 on the water jacket 14. The shaft 37 may be driven in any suitable manner from the engine. Operation of the shaft 37 need not necessarily be timed with the engine, although under some circumstances it may be desirable to synchronize registration of the pits or pockets 31 with the sump 22 with the explosions of the engine. Loss of compression is avoided since between each of the pockets 31 there is a substantial bearing land serving as a barrier to loss of compression.

45 Since the cleanout or drainage valve plug 25 rotates relatively slowly, there will be but a minimum of wear even though some carbon may get between the bearing surfaces of the valve plug 25 and the bushing 27. Such wear is minimized by affording constant lubrication of the substantial bearing surfaces at the opposite end 50 portions of the plug as may be provided by oil

ducts 39 leading from the forward lower end portion of the cylinder bore, through the cylinder wall and the valves boss 29 into the bushing 27 near the ends of the valve plug. As best seen in Fig. 1, the openings to the lubricating ducts 39 are located adjacent to the outer end of the cylinder bore in position to be lapped by the piston 11 when the latter moves from the partially advanced position as shown to the full compression position at the end of the cylinder bore. Thus, oil carried outwardly by the piston finds its way into the lubricating ducts 29 and thence to the valve plug 25.

To assure a snug bearing fit of the valve plug 25 at all times within the bearing bushing 27, a take up mechanism is preferably provided comprising a stem 40 projecting from the inner end of the valve plug through a bearing aperture 41 in the adjacent end wall of the valve boss 29 to which the adjacent end of the valve plug is located in spaced take-up relation, and beyond which the take-up stem projects to a substantial distance outwardly. A coiled compression take-up spring 42 acts between a threadedly adjustable compression collar 43 carried by the stem 40 and a longitudinally slidably thrust collar 44 keyed onto the stem. A bearing washer 45 is interposed between the thrust collar 44 and the adjacent outer face of the boss end wall. A lock nut 47 on the end of the stem 40 is designed to retain the compression collar 43 in adjusted condition. Thus, by placing the compression spring 42 under suitable pressure, the spring maintains a constant outward thrust take-up pressure on the take-up stem 40 and thus on the plug 25 to maintain the same at all times in snug bearing relation within the sleeve 27 whereby to avoid compression leakage past the plug.

It will thus be apparent that as the engine operates and carbon forms and drains as a sludge into the sump 22, the drainage pits or pockets 31 and the valve plug 25 continuously carry away the carbon accumulations and expel the same from the discharge opening 33, thereby eliminating the condition which has heretofore prevailed and under which the carbon eventually fouled up the compression chamber or found its way into the crank case.

In Figure 3 is shown schematically an engine, in this instance a two cylinder engine, in which a source of fuel 48 supplies gasoline, diesel oil or the like to the engine while a lubricating oil source 49 constantly supplies lubricating oil to the crank case 50 of the engine. Each of the cylinders, which is enclosed within a casing 51 embodies the principles of the present invention according to which the carbon is removed directly from the combustion or compression chamber of the cylinder and a small, controlled oil seepage past the piston is provided for as a flushing agent, the level of lubricating oil in the crank case being maintained constant by continuous replenishment from the lubricating oil supply 49.

In Figure 4 the invention is shown as applied to a vertically reciprocating cylinder and piston assembly wherein the combustion or compression chamber is at the top. In this form a vertically reciprocating piston 55 operates in a cylinder 57 having a compression chamber 58 at the top. Poppet valve controlled fuel inlet and outlet passages 59 and 60 communicate with the high portion of the compression chamber 58 while a sump depression 61 is provided at the lowest point in the compression chamber and preferably at one side of the cylinder 57. In

order to promote movement and drainage of carbon and sludge as may be occasioned by slight desirable oil leakage past the piston 55 into the compression chamber 58, the floor of the compression chamber together with the top of the piston are preferably sloped slightly toward the sump 61. Scavenging of the carbon is completed by drainage thereof from the sump 61 through the medium of a compression proof valve 62 which deposits the carbon sludge into an exhaust passage 63 which may lead to an appropriate receptacle or from which the sludge may simply drop, as preferred.

I claim as my invention:

1. In combination in an internal combustion engine including a cylinder and piston operable therein and a cylinder head providing a compression chamber having fuel inlet and exhaust passages leading from a high position therein, a sump depression at the lowest point in said compression chamber for collecting carbon gravitationally, and means effecting drainage from said sump while maintaining a compression tight closure for the sump, said means comprising a drainage pocketed plug valve rotatably mounted under said sump.
2. In combination in an internal combustion engine assembly, means defining a cylinder and piston structure and a compression chamber, fuel intake and exhaust gas outlet means communicating with a high portion of the compression chamber, a carbon scavenging sump at the lowest point of the compression chamber, a drainage valve assembly operative at the bottom of the sump, and means for lubricating said valve assembly including a lubricating duct leading from the cylinder.
3. In combination in an internal combustion engine assembly, means defining a cylinder, a piston operable in the cylinder, a compression chamber at the head of the cylinder, means affording fuel inlet and exhaust gas outlet at the high part of the combustion chamber, means defining a carbon scavenging sump at the low part of the combustion chamber, a taper bushing having an opening in the side thereof communicating with the sump, a plug valve slidably disposed in said bushing and having a series of sump drainage pits therein successively registrable with said drainage opening in the bushing in response to rotation of the plug valve, means affording a drainage opening from the bushing with which the loaded pits register in the turning of the valve, means for rotating the valve, and means for maintaining a take-up pressure on the plug valve to maintain a compression tight bearing relation between the plug valve and the bushing.
4. In combination in an internal combustion engine assembly, means defining a cylinder, a piston operable in the cylinder, a compression chamber at the head of the cylinder, means affording fuel inlet and exhaust gas outlet at the high part of the combustion chamber, means defining a carbon scavenging sump at the low part of the combustion chamber, a taper bushing having an opening in the side thereof communicating with the sump, a plug valve slidably disposed in said bushing and having a series of sump drainage pits therein successively registrable with said drainage opening in the bushing in response to rotation of the plug valve, means affording a drainage opening from the bushing with which the loaded pits register in the turning of the valve, means for rotating the valve, and lubricating means for the plug valve including a

duct leading from the cylinder through the bushing;

5. In combination in an internal combustion engine assembly, means defining a cylinder, a piston operable in the cylinder, a removable cylinder head closing the outer end of the cylinder, said cylinder head defining a combustion chamber cavity, fuel inlet and exhaust ports communicating with high portions of the combustion cavity, said cylinder head having a sump recess at the lowest portion of said combustion chamber cavity for collecting carbon sludge, a valve controlling the removal of carbon sludge from said sump recess, and means automatically operating said valve in the operation of the engine. 10

6. In combination in an internal combustion engine assembly, means defining a cylinder and a compression-combustion chamber at one end of the cylinder, said means including fuel inlet and exhaust ports at the high portion of the chamber, valves controlling said ports, said means also having a carbon sludge sump recess at the lowest

5 point of said chamber, all surfaces leading to the sump recess being smoothly curved on respective substantial radii generally greater than mere relieving of sharp corners, whereby to avoid any ledges on which carbon might tend to accumulate, a valve sludge ejector operable to scavenge the sump, and means for automatically operating said valve-ejector in the operation of the engine.
